UNITED STATES PATENT OFFICE

155,358

DESIGN FOR A COMBINED BOTTLE AND BOTTLE CAP

George Pavlinetz, Carteret, N. J.

Application November 28, 1947, Serial No. 142,863

Term of patent 14 years

(Cl. D58—6)

To all whom it may concern:

Be it known that I, George Pavlinetz, a citizen of the United States, residing at Carteret, in the county of Middlesex, State of New Jersey, have invented a new, original, and ornamental Design for a Combined Bottle and Bottle Cap, of which the following is a specification, reference being had to the accompanying drawing, forming part thereof.

Figure 1 is a top view of the combined bottle and bottle cap showing my new design; Figure 2 a front elevation, and Figure 3 a side elevation of the design shown.

I claim:

The ornamental design for a combined bottle and bottle cap, as shown.

GEORGE PAVLINETZ.
